UNITED STATES PATENT OFFICE

2,528,976

SEWING THIMBLE

Edward L. Schiavone, Silver Spring, Md.

Application March 5, 1947, Serial No. 732,555

2 Claims. (Cl. 223—101)

1

This invention relates to sewing thimbles. More particularly the invention pertains to a sewing thimble which presents one surface zone of hard material which is used to thrust the needle through the material being sewed and which presents another surface zone of frictional material which is used to draw the needle through the material and complete the sewing action.

The conventional sewing thimble has the disadvantage that it hinders, rather than helps, a person from drawing a needle through the material being sewed after the needle has pierced the material. This is because the conventional sewing needle is made throughout of a hard material which presents a slippery outer surface. When a needle is gripped between the thumb and the usual thimble, as in ordinary sewing practice, it is difficult to grip the needle with sufficient firmness to pull it through the material because the smooth surface of the thimble causes the needle to slip.

It is therefore apparent that the conventional sewing thimble partially defeats its own purpose. Sewing thimbles are employed to assist the manual sewing operation, especially when stitching thick or firm material. When thin or light weight material is being stitched, a thimble is not a necessity as the needle is easily pierced into the material and then is easily gripped between the fingers and withdrawn.

When sewing thick or firm materials, as, for example, heavy cloth fabrics or leather, the use of a thimble becomes a necessity in order to push the needle into the material. The thimble prevents the needle from piercing the fingers as the needle is being pushed into the material and therefore serves a highly important purpose. However, although the conventional thimble is useful in this respect, it makes it more difficult to grip the needle sufficiently tight to pull the needle through the thick or firm material.

Thus a conventional thimble is of considerable help to back-up a needle in pushing it through firm material, but because of the slippery outer surface of the conventional thimble it makes it harder to grip the needle to fully withdraw it through the fabric. In fact, the needle can be pulled more easily through the fabric by gripping it between the bare fingers, than it can be by gripping the needle against the conventional thimble.

In accordance with the present invention, a thimble is provided which gives valuable assistance both in the step of thrusting a needle into the material, and in the subsequent step of draw-

2

ing the needle through the material. When thick or firm material is to be sewn, and the use of a thimble is necessary to push the needle into the material, the use of the present thimble assists, instead of hinders the step of gripping the needle to pull it through the fabric. This dual advantage is obtained by providing the thimble with a hard, strong surface zone, and with a frictional surface zone.

10 Several possible embodiments of the invention are illustrated in the accompanying drawings, in which:

Figure 1 is a view showing the usual manner of gripping a needle to pull it through material being sewn, a thimble made according to the invention being used.

15 Figure 2, is a sectional view through the axis of a thimble of the invention.

Figure 3, is a sectional view on the line 3—3 of Figure 2.

20 Figure 4, is a sectional view through the axis of a modified form of the thimble.

Figure 5, is an elevational view of another modification of the invention, and

25 Figure 6 is a sectional view through the axis of the thimble of Figure 5.

Referring first to the thimble of Figures 2 and 3, the body 7 of this thimble is generally of conventional formation and material. Thus the body 7 is hollow to receive the end of the finger and is generally frusto-conical in shape to fit better on the finger. The top 8 or smaller end of the body is closed and the base or open end has a peripheral flange 9 to strengthen the body.

30 It is not material whether the wall of the body is of uniform thickness.

The body 7 may be made of any usual hard material, as metal or a rigid plastic. For example it may be of aluminum, or of one of the phenol-formaldehyde or urea-formaldehyde condensation products. Its outer closed end is formed with a plurality of small depressions to afford the usual needle seats.

35 As an important feature of the invention, the base portion of the thimble is provided with a body of frictional material 10. As here shown this frictional material is a band which completely encircles the base of the thimble, but this is not a necessary relationship as the frictional material may be upon only an arcuate portion of the outer surface.

40 Rubber, of the consistency usually employed for rubber bands, or erasers, is representative of the many materials which may be employed to provide the frictional surface. Other known

materials, as synthetic resins which present a frictional surface may be used. This frictional material may or may not contain some abrasive constituent to increase its frictional effect, as desired. For example, one of the abrasive materials employed in making the common ink eraser may be distributed throughout the frictional material 10 or may simply be embedded in its outer surface.

If the frictional material 10 is in the form of a band, as is here shown, it may be positioned upon the base of the thimble by simply passing it over one end of the thimble. The band preferably is made of such size that it will be under tension on the thimble and will thus retain itself in position. However, the frictional material may be cemented or vulcanized in place upon the thimble and this is to be practiced if the resilient material is merely around an arcuate portion of the base of the thimble.

To further assist in retaining the frictional material in place, if it is in the form of a band as shown, the base of the thimble may be formed with a circumferential groove 11 to receive the band. As here shown, the flange 9 forms a retaining shoulder at one side of the groove, but if the flange is absent, the groove should be a continuous channel around the thimble.

It has been mentioned that the frictional material 10 may be of a rubber like material, which does or does not contain an abrasive. In Figure 4 is shown a frictional material 12 which is principally of an abrasive material. For example this may be the abrasive containing substance which is applied to paper in making sandpaper or emery-cloth. This may be applied to the thimble and heated to set it and cause it to adhere to the thimble body. Or, the invention contemplates cutting a strip of ordinary sandpaper of the proper length and width and cementing its ends together after encircling it about the base of the thimble.

Another variation of the invention is shown in Figures 5 and 6, in which the body 13 of the thimble is of a frictional material such as rubber, a rubber-like plastic, or any substance such as that of the frictional material 12, which has sufficient strength. This body 13 is of the usual thimble shape and its base portion provides the frictional surface against which the needle is pressed as shown in Figure 1.

To the closed end of body 13 is applied a cap-piece 14 of hard, strong material such as metal or a firm plastic as, for example, one of the above formaldehyde condensation products. This cap-piece 14 is cemented, vulcanized, riveted, or affixed in any other manner to the closed end of the thimble. The outer surface of cap-piece 14 is indented in the usual manner to provide a plurality of needle seats.

It will be appreciated that the thimble of the present invention is so simple in construction that it can be made at a low cost. The elements of the thimble are easily fabricated and their assembly into the final thimble is readily performed.

I claim:

1. A sewing thimble comprising a hollow body of relatively hard, strong material, one end of said body being closed and the opposite end open, and a substantially wide flat resilient friction band encircling the body adjacent the open end thereof, said friction band being tightly held along the axial length of said body and extending a substantial distance therealong providing a frictional surface into which a needle may be pressed and frictionally held in pulling said needle through a material.

2. A sewing thimble comprising a hollow body of relatively hard, strong material, said body having a relatively wide circumferential groove therearound, said groove extending a substantial distance along the axial length of said body, and a band of substantially wide, flat resilient friction material encircling said body and seating in said groove, said friction material presenting a surface into which a needle may be pressed and frictionally held in pulling the needle through a material.

EDWARD L. SCHIAVONE.
